UNITED STATES PATENT OFFICE

2,452,853

CLOSED EDGE FLY FRONT FOR GARMENTS

Frank Ippoliti, Philadelphia, Pa.

Application June 2, 1947, Serial No. 751,815

2 Claims. (Cl. 2—96)

1

My invention relates to a new and useful fly front for garments, and has for one of its objects to provide a neat appearing fly front that cannot bulge or open up in a gapping manner.

Another object of this invention is to provide a garment with a fly front that is closed along the entire outer edge.

Another object of the invention is to provide a garment with a completely closed fly except for the button holes.

Another object of the present invention is to provide a closed edge garment fly which will conceal the buttons during the time the garment is buttoned in a closed or fastened condition.

A further object of the invention is to arrange one layer of the lining or other interior material in a manner to cover the raw edges of the materials within the fly whereby said raw edges will be concealed from sight through the buttonholes and ravelings cannot enter the button space between the walls or plies of garment material.

A still further object of this invention is to form a closed fly for garments which will be strong, wear-resisting and in which only the garment material is visible under any and all conditions, thereby eliminating any possibility of unsightly worn lining being seen by persons in the vicinity of the wearer of a garment fashioned with the closed fly.

With the above and other objects in view this invention consists of the details of construction and combination of elements hereinafter set forth and then designated by the claims.

In order that those skilled in the art to which this invention appertains may understand how to make and use the same I will describe its construction in detail, referring by numerals to the accompanying drawing forming a part hereof, in which:—

Fig. 1 is a front view of a conventional overcoat, illustrative of a garment constructed with my closed fly, a portion of the coat being thrown or turned back to show the relation of the buttons and the buttonholes in the fly part of the garment.

Fig. 2 is an enlarged and exaggerated horizontal section through the two layers or sections of garment material extended and sewn together as the preliminary step in the formation of the closed fly.

Fig. 3 also is a horizontal or transverse section of the closed fly.

Fig. 4 is a similar view of the complete garment closure including the closed fly.

2

Fig. 5 is a transverse section of a closed fly of slightly different formation.

In carrying out my invention as herein embodied 7 and 8 represent the two parts of the closure of a garment 9 which, for purposes of illustration only, is shown as an overcoat. The part 7 has the buttons 10 sewn thereon by the stitches 11 and the part 8 has portions fashioned to constitute the closed fly 12 defined and bordered by the row of stitches 13, Fig. 1.

Principally, the closed fly includes an inner wall or ply 14 of garment material having buttonholes 15, and an outer wall or ply 16 of garment material in spaced parallel relation to said inner wall or ply 14 to provide a button space 17 and the forward edges of said walls or plies are sewn together to form a seam 18.

Actually, each wall or ply of garment material 14, 16 has any desired number of layers of stiffening fabric 19 and 20, respectively and lining fabric 21 and 22, respectively. The two plies of garment material, Fig. 2 with the respective imposed layers of stiffening and lining fabrics, especially the latter, are laid together, face to face, and sewn by the row of stitches 23 to form the seam 18. After this has been done, the two plies or walls of garment material are folded back, the start of which is shown in Fig. 2, until they are, in effect, completely folded inside out and in spaced parallel relation, as depicted in Figs. 3 and 4. Thus folded, a closed outer edge 24 is formed as well as the button space 17 being provided to which access is had only through the buttonholes.

With the above construction, under some extreme condition, the raw edges of the inturned portions of the goods forming the seam 18 might become visible through the buttonholes but this is completely overcome by first imposing both linings 21 and 22 on the same wall or ply of garment material and carrying one of said layers of lining fabric over to the other wall or ply of fabric material as shown in Fig. 5. In this last mentioned figure both lining fabrics 21 and 22, by way of illustration, are shown imposed on the wall or ply of garment fabric 14 and the seam 18 is then formed as previously described. When the two walls or plies of garment fabric are turned back, the top or outermost layer of lining fabric, as 22, is moved over and imposed on the other wall or ply of garment fabric 16 thereby being disposed across and concealing the raw edges of the seam 18 so they will not be visible through the buttonholes under any condition.

From the foregoing it will be apparent that when a garment constructed with the closed fly

of this invention is buttoned, the buttons are completely concealed and there is no possibility of the garment fabric gaping open, thus the fly is as neat appearing as any other finished edge of the garment.

Of course I do not wish to be limited to the exact details of construction herein shown and described as these may be varied within the scope of the appended claims without departing from the spirit of my invention.

Having described my invention what I claim as new and useful is:

1. A garment fly comprising an inner and an outer wall or ply of garment material disposed in parallel spaced relation, with the outer edges turned in and secured together to form a seam located between the walls of garment material, the inner wall having buttonholes as the only access to the space between the garment walls, and two layers of lining material having contiguous edges of both layers secured to the seam between one side thereof and one adjacent garment wall, one of said lining layers extending over the inside surface of said adjacent wall, and the other lining layer being separated from the first mentioned lining layer and extending over the inside surface of the opposite garment wall and covering the in-turned seam to conceal the latter from view through the buttonholes.

2. The method of forming a closed fly on a garment which consists of laying two walls or plies of garment material face to face, imposing two layers of lining material on the then outer face of only one garment material wall and sewing all of the garment walls and lining layers together along one edge, then forming buttonholes in one garment wall and the contiguous lining layer, then folding said walls back upon themselves in the region of the seam whereby the raw edges of said seam will be inturned, then separating the outermost lining layer from the other lining layer and disposing said outermost lining layer over the raw edges of the seam and the inner surface of the opposed garment wall.
